UNITED STATES PATENT OFFICE

ROBERT C. HANSON AND IVAR JEPSSON, OF CHICAGO, ILLINOIS, ASSIGNORS TO CHICAGO FLEXIBLE SHAFT COMPANY, OF CHICAGO, ILLINOIS, A CORPORATION OF ILLINOIS

DESIGN FOR A HEALTH LAMP

Application filed October 17, 1929. Serial No. 33,084. Term of patent 3½ years.

To all whom it may concern:

Be it known that we, ROBERT C. HANSON and IVAR JEPSSON, citizen of the United States, and subject of the King of Sweden, respectively, residing at Chicago, in the county of Cook and State of Illinois, have invented a new, original, and ornamental design for a Health Lamp, of which the following is a specification, reference being had to the accompanying drawing, forming part thereof.

In the drawing—

Fig. 2 is a side elevation thereof.

We claim:

The ornamental design for a health lamp, as shown.

ROBERT C. HANSON.
IVAR JEPSSON.
